VARICOLORED LIGHT

Harry C. Davis, Brighton, Mass.

Application December 22, 1934, Serial No. 758,849

4 Claims. (Cl. 240—10)

This invention relates to new and useful improvements in vari-colored lighting units, and it is among the objects thereof to provide a unit light bulb which changes color automatically and continuously in a predetermined cycle.

A further object of the invention is the provision of a plurality of incandescent colored light tubes within a glass housing of bulbous shape in which the tubes are successively energized to produce a different color effect in the bulb.

Still another object of the invention is the provision of means within the above mentioned vari-colored lighting unit for successively energizing and deenergizing the several light tubes in successive cycles and reverse order, and to provide simple and inexpensive mechanism for carrying out this function.

These and other objects of the invention will become more apparent from a consideration of the accompanying drawings constituting a part hereof in which like reference characters designate like parts and in which:

Fig. 1 is a plan view partially in section of a vari-colored lighting unit embodying the principles of this invention;

Fig. 2 a side elevational view thereof showing the glass bulb or housing in section;

Fig. 3 a plan view of the control unit located in the base;

Fig. 4 a side elevation of the control switch and end portions of a thermal element;

Fig. 5 a plan view of the switch element;

Fig. 6 an end elevation of a portion of the switch;

Fig. 7 a plan view of a portion of the annular incandescent colored lighting tubes;

Fig. 8 a cross-section of the tube of Fig. 7;

Fig. 9 a side elevational view of the supporting frame for the tube; and

Fig. 10 a diagrammatic view of the electrical connections of the tube and control mechanism.

The vari-colored lighting unit comprises a plurality of annular incandescent light tubes 1 mounted in superposed relation as shown in Fig. 2 supported by wire stanchions 2 on a base 3 of insulating material such as the well known phenolic condensation product. The tubes 1 are independent lighting units of different colors housed within a frosted glass bulb 4 which may be detachably or permanently secured to the insulating base 3.

With reference to Fig. 9 of the drawings, the tubes 1 are supported on a wire frame 5 forming hook-like elements 6 for engaging the tubes 1, the lower one of which is shown in assembled position. The tubes of colored glass are provided with

a filament 7 having terminals 8 and 9, the filament 7 being disposed centrally of the tube and spaced from the walls thereof by mica disks 10 or other suitable means.

A control mechanism for independently energizing the colored tubes 1 is shown in Figs. 3, 4, 5, 6 and 10 of the drawings, and consists of a bi-metallic member of annular form, the outer section 11 being a metal strip of relatively high thermal expansion such as brass and the inner section 10 5 12 a metal strip of relatively low thermal expansion such as iron, the metal strips 11 and 12 being fused together and enclosed within a coil 13 of insulated resistant wire arranged to heat the band and expand it uniformly. One end of the band is 10 anchored in a block 14, Fig. 4, the other end 15 being free to move. The end 15 is provided with a depending arm 16 which is perforated to receive a terminal pin 17 that is biased by a leaf spring 18 against a switch bar 19. The switch bars or terminals 19 are in multiples corresponding to the number of colored tubes in the lighting unit and are separated by suitable insulating material 20 as shown in Figs. 4 and 5. The terminal pin 17 is adapted to traverse across the bars 19 between 20 25 a pair of stops 21 and 22 which constitute switch terminals for the insulated resistance wire 13 of the bi-metallic element. The terminals 21 and 22 are shaped in the manner shown in Fig. 6 having in-turned ends and common runners 23 30 for grippingly engaging slots 24 of insulating base 25 that supports the terminal bars 19. The ends 23 of stops 21 and 22 constitute runners in the slot 24 of the switch block 25. A metal lining 26 in two sections, the one to which pigtail 30 is connected being the shorter is provided in groove 24, the lining being interrupted to form a gap at one end of each runner 23 which breaks the circuit of the resistance coil 13. When arm 16 abuts the switch stop 22, the metal unit, or sliding switch, composed of stops 21 and 22 on common gripping runners 23 is moved, by means of continued expansion of members 11 and 12, away from the shorter section of the metal lining 26 around the gap, disconnecting the resistance coil circuit so 40 that the resistance will be deenergized, permitting the bi-metallic strips to cool and causing the element to contract, and when stop 16 again abuts the member 21, the circuit of resistance coil 13 will be energized to again heat the bi-metallic unit to cause expansion and further movement of arm 16.

Fig. 10 diagrammatically illustrates filaments 7 of the tubes as connected by a negative lead 27 to the fixed end 28 of the resistance coil 13. A post- 55

tive lead 29 runs through the bi-metallic member 11 and 12, the depending arm 16 and the terminal pin which moves upon the filament switch plates 19 and to the longer section of the metal lining 5 26 in groove 24 in the sides of the filament switch block 25. A pigtail 30 connects the other section of the runway 24 with the movable end of the resistance coil 13.

The operation of the above described vari- 10 colored light bulb is briefly as follows:

The unit is screwed in a standard terminal socket as any other light bulb and switch arm 16 will be in the contracted position with the terminal pin 17 contacting one of the switch plates 15 19 to energize one of the colored tubes. Simultaneously, resistant coil 13 will be energized, heating the bi-metallic unit and causing expansion thereof to effect a corresponding movement of terminal pin 17 from the switch plate 19 20 to the next adjacent plate thereby breaking the circuit of one bulb and making the circuit of another. Making and breaking of the annular colored light bulb circuits is continued until the switch arm 16 abuts the switch terminal 22 thereby 25 deenergizing the circuit of resistance coil 13 causing cooling of the bi-metallic member and consequent opening of the ring with the movement of arm 16 in the opposite direction. Such movement of arm 16 will again cause the terminal pin 17 to traverse switch plates 19, to effect successive lighting of the different colored tubes 1 until arm 16 abuts stop 21 in its ultimate contracted position when the circuit of resistance coil 13 will again be energized to heat the bi-metallic member and cause repetition of the cycle 30 of successive lighting in both directions of movement produced by the bi-metallic unit.

The frosted glass bulb 4 housing the colored tubes 1 will appear as any other lighting unit, 40 and will assume the different colors in accordance with the energization of the respective colored tubes. It will be noted that the colored tubes are incandescent by direct current instead of by induction. The frosted bulb and colored tubes 45 may be constructed so as to be detachable and replaceable in the event of filament burn-outs.

While due to inaccuracy in manufacture, a group of these lamps cannot be expected to operate synchronously for any length of time, it is 50 apparent that if operated in conjunction with a master switch controlling a group they will perform with sufficient regularity. By periodically disconnecting the entire circuit to cause a general contraction of the bi-metallic element, a uniform start may be effected upon reconnection. 55 If a master switch be omitted, the aforementioned irregularity will present an unusual and attractive display in color harmony in unending variation.

60 It will be apparent from the foregoing description of this invention that multi-colored light units may be economically produced for display purposes with unlimited variety in colors and at

a minimum expense. The units further permit operation in groups without interrupting the lighting display if one of the units burns out or is disconnected.

Although one embodiment of the invention 5 has been herein illustrated and described, it will be obvious to those skilled in the art that various modifications may be made in the details of construction without departing from the principles herein set forth.

10 I claim:

1. A vari-colored illuminating device comprising a plurality of colored incandescent light tubes mounted on an insulating base, a glass housing for said tubes, and a control switch in said base 15 for energizing the circuits of said lighting tubes, said switch comprising a plurality of stationary terminals each connected to one terminal of the several colored tubes and a movable terminal adapted to successively contact said stationary 20 terminals, said movable terminal being mounted on a bi-metallic element having a resistance coil therearound, and terminating in switch blocks disposed in the path of travel of said movable terminal whereupon the resistance coil is alternately energized to heat the bi-metallic element 25 that actuates said movable terminal in its travel across the stationary terminals.

2. A vari-colored illuminating unit comprising a plurality of colored incandescent lighting tubes 30 mounted on an insulating base, having electrical connections for an outlet socket, a bulb housing said tubes, and a control mechanism for energizing and deenergizing said colored lighting tubes, said mechanism comprising a bi-metallic 35 unit having an arm movable in response to expansion and contraction thereof, an electrical terminal carried by said arm, a plurality of stationary terminals connected to said colored light tubes, a resistance coil for heating said bi-metallic element and switch terminals in the path of 40 movement of said movable terminal for energizing and deenergizing said resistance coil to cause successive movement of the movable terminal to make and break the circuits of said colored tubes.

3. A mounting for a plurality of annular shaped incandescent lighting tubes of different diameter of annulus comprising a wire support having a series of spaced tube engaging elements inclined to receive the incandescent tubes of 45 graduated diameters.

4. A support for a plurality of annular shaped incandescent lighting tubes of different diameters comprising a plurality of angularly spaced inclined supporting members recessed to receive and support the tubular member thereon, whereby when viewed from the side the incandescent tubes have the appearance of being in superposed relation and when viewed at the top as consisting of a plurality of concentric incandescent 55 rings.

60 HARRY C. DAVIS.
